FEELER MECHANISM FOR LOOMS.

1,286,412.

Specification of Letters Patent.

Patented Dec. 3, 1918.

Application filed August 29, 1916. Serial No. 117,552.

To all whom it may concern:

Be it known that I, ALONZO E. RHOADES, a citizen of the United States, and resident of Hopedale, county of Worcester, State of Massachusetts, have invented an Improvement in Feeler Mechanism for Looms, of which the following description, in connection with the accompanying drawing, is a specification, like characters on the drawing 10 representing like parts.

This invention relates to improvements in automatic looms in which the feeler enters the running shuttle to feel upon the filling carrier therein and upon detection of substantial 15 exhaustion of filling initiates the action of mechanism which effects a change in the operation of the loom, such as the substitution of a fresh filling carrier for an exhausted one, or serves to stop the loom.

20 In usual loom constructions the feeler enters the shuttle box through the front wall thereof and is operated by contacting with the filling upon the filling carrier upon the beat-up of the lay. In such case the binder 25 which arrests the shuttle is usually located at the rear side of the shuttle box and diverts the shuttle away from the plane of the reed upon the lay as it enters the shuttle box.

30 In making hard weaves, particularly upon wide looms it is found that the loom will act more effectively if the shuttle is not inverted in this manner away from the plane of the reed, it is desirable therefore that the shuttle 35 boxes be equipped with front binders. When therefore, the usual feeler is employed it is necessary to cut an aperture through the front binder and inasmuch as the shuttle engaging surface of the binder is curved, 40 the edges of the walls of the aperture wear away the shuttle quite rapidly.

The object of the present invention is to provide a loom having front binders with feeler mechanism which will not necessitate the cutting of an aperture through the binder. This is accomplished in the preferred embodiment of the invention illustrated herein by mounting the feeler upon the lay and so positioning the same that it enters the rear wall of the shuttle box to feel upon the filling carrier in the running shuttle.

45 In order not to interfere with the flight of the shuttle, the feeler is normally withheld from feeling position and means are

provided which act upon the beating-up of the lay to advance the feeler to feeling position and upon detection of substantial exhaustion of filling upon said filling carrier to initiate the action of mechanism for 60 effecting a change in the operation of the loom.

The drawings illustrate a preferred embodiment of my invention applied to an automatic filling replenishing loom but it will be understood that the feeler may be utilized to effect other changes in the operation of the loom such as the stoppage thereof.

In the drawings:

Figure 1 is a plan view of the end of the 70 loom frame including the breast beam and shipper plate and a section of the end of the lay and shuttle box carried thereby showing the improved feeler mechanism applied thereto,

Fig. 2 is an end view showing the feeler mechanism applied to the loom and illustrating the shuttle box, shuttle and filling carrier in section,

Fig. 3 is a front elevation of the standard 80 which supports the transmitter operating lever, a portion of the end of the transmitter and its bearing being shown.

The invention is illustrated herein as applied to the "Northrop" type of automatic 85 filling replenishing loom which is provided with transferring mechanism for automatically thrusting a fresh filling carrier into the running shuttle and ejecting the used carrier therefrom. said transferring mechanism being controlled by the usual controller shaft having a latch adapted to be positioned in the path of a moving actuator upon call for transfer and operated by said moving actuator to cause the proper operation of the transferring mechanism.

Inasmuch as these mechanisms are well known their illustration is unnecessary, so that only a portion of the end frame of the loom showing the feeler and the mechanisms 100 with which it immediately co-operates are illustrated in the drawing.

The drawing illustrates the end of the usual breast beam 1, having a shipper plate 2, attached thereto provided with the usual 105 L-shaped slot 3, to receive the shipper 4. A knockoff lever 5 engages said shipper and may be operated manually or by automatic mechanism of the usual character (not shown).

The usual controller shaft 6 is provided with an arm having a bifurcated end 7 in which the end of a latch 8 is mounted, the opposite end of said latch preferably lying normally in the path of a moving actuator 9 such as the weft hammer. These mechanisms may be and are of usual construction.

The latch 8 is adapted to be moved out of operative relation to the moving actuator 9 by a suitable transmitter which is actuated by the feeler mechanism in a manner hereinafter to be described.

The shuttle boxes 10 are preferably provided with relatively thick rear walls 11, and the binders 12, which may be of a usual type, are carried by the front walls, so that as the shuttle 13 is arrested it is pressed against the rear wall of the shuttle box and its path of flight directed closely adjacent the reed.

The shuttle may be equipped with the usual types of filling carrier employed in filling replenishing looms, but preferably is provided with a bobbin 14 having a feeling slot 15 in its barrel adapted to receive the feeler upon substantial exhaustion of the filling upon the bobbin.

In order to avoid cutting through the binder and thereby weakening the same and causing it to present edges which wear the shuttle, a novel feeler mechanism is provided in which the feeler enters the shuttle through the rear wall of the shuttle box, the feeler supporting mechanism preferably being mounted upon the rear wall of the shuttle box.

In the preferred embodiment of the invention shown herein the feeler is in the form of a rod 16 slidably mounted in an aperture 17 in the rear wall of the shuttle box, and is pivotally connected at its outer end to the lower end of a lever 18. The lever 18 is provided, intermediate of its ends, with a hub which is mounted upon a stud 19 projecting laterally from a stand 20 suitably secured to the rear wall of the shuttle box. The stand 20 is provided with an upward extension 21 having a guide 22 for an arm 23 which is pivotally connected to the upper end of the lever 18. The pivotal connections between the lever 18 and the feeler 16 and arm 23 respectively have sufficient play to permit the slight arcuate movement of the lever 18 without causing the feeler or arm to bind in their guides 17 and 22.

In order not to interfere with the flight of the shuttle it is necessary that the feeler shall be normally withheld from feeling position and this conveniently is accomplished by a spring 24 preferably encircling the hub upon the lever 18 and anchored at one end to a pin on the stud 19 and at the other engaging the lever 18 in such a manner as normally to remove the feeler from feeling position, a stop 25 being provided upon the extension

21 of the stand 20 to limit the movement of the lever 18 under the action of the spring 24.

The mechanism which coöperates with the feeler thus described preferably comprises a lever 26 having a central hub pivotally mounted upon a stud 27 projecting laterally from a stand 28 which desirably is adjustably secured by a bolt 29 to a flange 30 depending from the end of the shipper plate, the lever 26 being provided at its upper end with a member 31 pivotally connected to the lever 26 and extending through a guide 32 in an extension 33 of said stand, so that the end of the member or arm 31 is in alignment with the end of the arm 23 of the feeler mechanism.

A screw 33 seated in the end of the arm 31 and adapted to be secured in adjusted position therein by a lock nut 34 provides means whereby the coöperative relation of the members 31 and 23 may be regulated to adapt the feeler for use with filling carriers of different diameters or with shuttles of different width.

A spring 35 anchored at one end to a pin on the stud 27 and encircling the hub of the lever 26, and at the other end engaging the lever 26 serves normally to rock the upper end of the lever 26 toward the feeler mechanism and its movement in that direction is limited preferably by a stop 37 projecting from the extension 33 of the stand 28 into the path of the upper portion of the lever.

The lever 26 is operatively connected at its lower end to a suitable transmitter which is adapted to move the latch in relation to the moving actuator under the control of the feeler mechanism upon detection by the feeler of the condition of the filling upon the filling carrier.

A preferred form of transmitter which is illustrated herein comprises a rock shaft 38 mounted in bearings 39, 40 in the end of the yoke 41 which has an upwardly extending flange 42 adjustably connected by a bolt 43 with a lug or flange 44 extending upwardly from the shipper plate 2.

The rock shaft 38 is provided at one end with a crank 45 which is pivotally connected to the lower end of the lever 26. At its opposite end the rock shaft is provided with an offset portion or crank 46 which engages a suitable slot 47 in the end portion of the latch 8.

When the rock shaft or transmitter 38 is oscillated by the movement of the lever 26 it serves to shift the position of the latch relatively to the path of the end of the moving actuator 9 as is usual in automatic loom constructions. In some instances the latch is normally maintained in the path of the moving actuator and removed therefrom so long as the feeler engages the filling upon the filling carrier and remains in the path

of the actuator when the feeler detects substantial exhaustion of filling, in other instances the reverse operation takes place. The present mechanism may be adapted to operate with either of these constructions. As illustrated herein the controller latch normally lies in the path of the moving actuator and is removed from said path by the engagement of the feeler with the filling 10 upon the filling carrier.

In the operation of the machine the feeler 16 is normally withheld from feeling position by the action of the spring 24 upon the lever 18, the lever 18 being retained in the 15 dotted line position illustrated in Fig. 2. As the lay approaches the fell of the cloth the arm 23 engages the screw 33 at the end of the member 31 which is connected to the lever 26 and is rocked so that the feeler is 20 thrust into the shuttle against the filling upon the filling carrier. When the feeler engages a predetermined amount or bunch of filling upon the filling carrier (when the usual form of filling carriers are used) or 25 when the feeler engages a layer of filling covering a feeling slot in a bobbin of the character illustrated in Fig. 3 the oscillation of the lever 18 is arrested and further movement of the lay toward the fell of the cloth 30 causes the lever thus restrained, acting through the arm 23, to force the member 31 forwardly thus rocking the lever 26 about its pivot 27. By this action the lower end 35 of the lever 26 oscillates the crank 45 of the transmitter 38 and the opposite end 46 of the transmitter depresses the end of the latch 8 beneath the path of the vibrating actuator 9 thereby preventing the action of the transferring mechanism. When, however, 40 the filling upon the filling carrier is exhausted to a predetermined amount, or in the mechanism illustrated uncovers the bobbin slot 15, the end of the feeler enters the slot 15 and does not actuate the levers 18 and 26 so that the latch 8 remains in the 45 path of the vibrating actuator 9 and upon forward movement of the latter is caused to rock the controller rod 6 and thereby to 50 initiate the action of the transfer mechanism.

By the mechanism herein illustrated and described a relatively simple feeler mechanism is provided which is adapted for looms having shuttle boxes with front binders. Furthermore, the mechanism is of such a character that it readily may be applied to usual forms of looms, particularly those of the "Northrop" type without material modification of the loom structure.

It is to be understood that the embodiment of the invention herein disclosed is of an illustrative character merely and that various other mechanisms may be provided for accomplishing the same purpose.

Having thus described my invention what

I claim as new and desire to secure by Letters Patent is:

1. In an automatic loom, a feeler positioned to enter the rear side of the shuttle box and feel upon the filling on the filling carrier in the running shuttle, means normally withholding the feeler from feeling position, coöperating means positioned to be engaged thereby upon the beat-up of the lay and advance the feeler to feeling position, said coöperating means operating upon detection by said feeler of substantial exhaustion of filling upon the filling carrier to effect a change in the operation of the loom.

2. In an automatic loom a feeler mounted upon the lay and positioned to enter the rear side of the shuttle box and feel upon the filling carrier in the running shuttle, yieldable means normally acting to withhold the feeler from feeling position and coöperating yieldable means adapted to engage the feeler withholding means upon the beat-up of the lay and advance the feeler to feeling position, said coöperating means being operable upon engagement by the feeler with filling upon the filling carrier to prevent a change in the operation of the loom but operating upon detection by said feeler of substantial exhaustion of filling upon the filling carrier to effect the change in the operation of the loom.

3. In an automatic loom, a feeler carried by the lay and positioned to enter the rear side of a shuttle box and feel upon the filling carrier in the running shuttle, means acting normally to withhold said feeler from feeling position, yieldable means carried by the breast beam of the loom for advancing the feeler to feeling position upon the beat-up of the lay and adapted upon detection by said feeler of substantial exhaustion of filling upon the filling carrier to effect a change in the operation of the loom.

4. In an automatic filling replenishing loom, a feeler mounted upon the lay and positioned to enter the rear side of the shuttle box and feel upon the filling on the filling carrier in the running shuttle, spring actuated means normally withholding the feeler from feeling position, coöperating yielding means adapted to advance the feeler to feeling position upon the beat-up of the lay and operating upon detection by said feeler of substantial exhaustion of filling upon the filling carrier to effect a change in the operation of the loom.

5. In an automatic loom a feeler mounted upon the lay and positioned to enter the rear side of the shuttle box and feel upon the filling carrier in the running shuttle, a spring actuated lever connected to said feeler and normally acting to withhold the feeler from feeling position, means carried by a stationary part of the loom positioned

- to oscillate said lever to advance the feeler to feeling position and itself operable by said lever upon engagement by the feeler with filling upon the filling carrier to prevent a change in the operation of the loom but operating upon detection by the feeler of substantial exhaustion of filling upon the filling carrier to effect a change in the operation of the loom.
- 10 6. In an automatic loom a feeler mounted upon the lay and positioned to enter the rear side of the shuttle box and feel upon the filling carrier in the running shuttle, a spring actuated lever connected at one end to said feeler and normally acting to withhold the feeler from feeling position, an arm connected to the opposite end of said lever, yieldable means carried by the stationary part of the loom adapted to engage 15 said arm and advance the feeler to feeling position and operable by said feeler upon engagement by the latter with the filling upon the filling carrier to prevent a change in the operation of the loom but operating 20 upon detection by the feeler of substantial exhaustion of filling upon the filling carrier to effect a change in the operation of the loom.
7. In an automatic loom a feeler carried 25 by the lay and positioned to enter the rear side of the shuttle box and feel upon the filling carrier in the running shuttle, a lever connected at one end to said feeler, a relatively light spring acting upon said lever normally to withhold the feeler from feeling position, an arm connected to the opposite end of said lever, means comprising a spring of greater strength than that of the spring for the feeler actuating lever 30 adapted to engage the feeler actuating lever upon the beat-up of the lay whereby the feeler is advanced to feeling position and upon engagement with the filling upon the filling carrier causes the actuation of both 35 of said levers in the opposite direction and means operable by said means to avoid the action of the transferring mechanism but adapted upon detection by said feeler of substantial exhaustion of filling to effect 40 the change in the operation of the loom.
8. In an automatic filling replenishing loom comprising a transferring mechanism and means for operating the same including a controller having a latch adapted to 45 operate with a moving actuator, a transmitter engaging said latch, means for operating said transmitter comprising a lever having a spring acting normally to maintain said latch in operative relation to said moving actuator, a feeler mounted upon the lay and positioned to enter the rear side of the shuttle box and feel upon the filling carrier in the running shuttle, a spring actuated lever connected at one end to said feeler and at its opposite end to an arm positioned 55
- in operative relation to a member carried by the transmitter operating lever whereby upon the beat-up of the lay the engagement of said member with the arm upon the feeler actuating lever will advance the feeler to 70 feeling position and upon engagement with the filling on said filling carrier and upon further movement will actuate said levers and said transmitter to remove the latch from the path of the moving actuator but 75 upon detection of substantial absence of filling will permit engagement by said latch with the moving actuator to cause the action of the transferring mechanism.
9. In an automatic filling replenishing 80 loom comprising a transferring mechanism and means for operating the same including a controller having a latch adapted to cooperate with a moving actuator, a transmitter comprising a rock shaft having an offset end engaging said latch and provided at its opposite end with a crank, a lever pivotally mounted upon a stationary portion of the loom frame connected to said crank, a spring engaging said lever and normally 85 acting to retain said latch in operative relation to a moving actuator, a member connected to the opposite end of said lever overlying the path of the lay, a feeler mounted upon said lay to enter the rear wall of the 90 shuttle box and feel upon the filling carrier in the running shuttle, a spring actuated lever connected at one end to said lever and operating normally to withhold the feeler from feeling position, an arm connected to the opposite end of said lever adapted to engage said member upon the beat-up of the 95 lay whereby upon said engagement of said arm with said member the feeler will be advanced to feeling position and upon engagement with the filling upon the filling carrier will actuate said transmitter operating lever and transmitter to remove the latch from the path of the moving actuator and upon detection of substantial exhaustion 100 of filling will permit the latch to remain in the path of the moving actuator thereby causing the action of the transferring mechanism.
10. In an automatic filling replenishing 105 loom comprising a transferring mechanism and means for operating the same including a controller having a latch adapted to cooperate with a moving actuator, a transmitter engaging said latch, means for operating said transmitter comprising a lever having a spring acting normally to maintain said latch in operative relation to said moving actuator, a feeler mounted upon the lay and positioned to enter the rear side of the 110 shuttle box and feel upon the filling carrier in the running shuttle, a spring actuated lever connected at one end to said feeler and at its opposite end to an arm positioned in 115 operative relation to a member carried by 120
- 125
- 130

the transmitter operating lever whereby upon the beat-up of the lay the engagement of said member with the arm upon the feeler actuating lever will advance the feeler to 5 feeling position and upon engagement with the filling on said filling carrier will actuate said levers to remove the latch from the path of the moving actuator and upon detection of substantially absence of filling will permit 10 engagement by said latch of the end of the actuator to cause the action of the transferring mechanism and adjustable means carried by said arm adapted to control the amplitude of movement of said feeler whereby the same may be adjusted to co- 15 operate properly with bobbins of different size.

In testimony whereof I have signed my name to this specification.

ALONZO E. RHOADES.
